UNITED STATES PATENT OFFICE.

HIO P. EILERS, OF NEW YORK, N. Y.

BOOK-PAGE-RECORDING DEVICE.

1,018,816.

Specification of Letters Patent. Patented Feb. 27, 1912.

Application filed March 11, 1911. Serial No. 613,911.

To all whom it may concern:

Be it known that I, Hio P. EILERS, a citizen of the United States, and a resident of New York city, in the county of New York and State of New York, have invented certain new and useful Improvements in Book-Page-Recording Devices, of which the following is a specification.

The invention relates to recording devices for recording the number of the page at which a reader ceases reading a book and to which page he wished to at once open to resume his reading in subsequently taking up the book again for reading.

The objects of the invention will be set forth hereinafter in part, and will in part be obvious to those skilled in the art.

The invention consists in the novel parts, constructions, arrangements, combinations and improvements, herein shown and described.

The accompanying drawings, referred to herein and forming a part hereof, illustrate one embodiment of the invention, the same serving in connection with the description herein to explain the principles of the invention.

Of the drawings:—Figure 1 is an elevation of a book provided with the page recording device; Fig. 2 is a fragmentary section on the line A—B of Fig. 1, and upon an enlarged scale; Fig. 3 is a fragmentary perspective view showing the lining sheet side of the book cover of Fig. 1; and Fig. 4 is a view corresponding to Fig. 3 showing a somewhat different arrangement of parts.

Referring to the accompanying drawings and to the embodiment of the invention therewith illustrated, 1 represents the side cover of a book, and 2 the back of the book. The side of the cover may be constructed in any suitable manner, but is shown herein of a construction which is quite usual in what are ordinarily termed cloth-bound and leather-bound books of ordinary literature. That is, the side cover consists of several members or parts, usually a piece of binder's board having on the outside thereof the exterior leather or cloth cover folded over the binder's board at the edges, and pasted or otherwise attached to the surface of the binder's board, folded over the edges thereof and turned over the edges and folded over against the other side of the binder's board. A lining sheet of slightly less extent than the full area of the

side cover is usually pasted or otherwise attached on the inside of the side cover and over the folded over edges of the leather or cloth, thus making the work complete and 60 sightly. In Fig. 2 the sheet of binder's board is indicated by 3, and the external cloth or leather by 4 folded over and attached to the inside of the sheet 3 of binder's board at 5. The lining sheet is 65 indicated by the reference numeral 6. Located between two of said cover members are a plurality of movable members, each bearing a series of numerals, one of the cover members being apertured to permit 70 simultaneous observation of one numeral on each of said movable members, so that they may be read together to indicate the number of the page which the reader of the book wishes to record. The movable members are 75 shown as three disks 7, 8 and 9, rotatably fixed to the sheet 3 of binder's board, and also, if desired, to the outside cover 4. The disks are shown attached by eyelets 10, each eyelet serving as an axis about which the 80 disk rotates. Each disk is provided with the numerals or digits in a circular series upon its side, and the disks are shown one overlapping the other to economize space.

In Figs. 1, 2 and 3 the numerals are arranged to be observed from the exterior of the book and in Fig. 4 they are arranged to be observed from the interior. In Figs. 1, 2 and 3, the side of the book is accordingly apertured through the external cover 85 4 and through the binder's board 5, so as to expose a numeral on each of the disks. Three apertures 11, 12 and 13 are 90 shown formed by eyelets or rings set into the cover with the flanges thereof turned over the parts 4 and 5, and each aperture being in register with the circle of numerals on the corresponding disks 7, 8 or 9; each aperture being of a size to expose one numeral only.

The edges of the disks 7, 8 and 9 project very slightly beyond the edge of the cover so that each of the disks may be turned by the finger of the reader and yet is unlikely to be disturbed accidentally by any 105 other means. The lining sheet 6 covers the disk except for a small space where they project to be actuated by the reader's finger, as will be clear from Fig. 2.

In Fig. 4 the page recording device is 110 shown readable from the inside of the cover only and, if desired, may be constructed and

arranged so that no evidences of it are discernible from the exterior of the book. In such an arrangement the eyelet 10 may extend only through the binder's board 3, 5 the exterior cover member 4 being continuous past it. The apertures 11, 12 and 13 in such case are formed in the lining sheet 6 and, of course, the numerals are on the opposite face of the disk from the arrangement shown in Figs. 1, 2 and 3. In Figs. 3 10 and 4 the body of the book is indicated by 14 and the other cover by 15. In Figs. 1, 2 and 4 the exposed or visible numerals on the disks are indicated by 16.

15 With the device of the present invention, the turning down of pages, the withdrawing and re-inserting of a movable and projecting book mark, or the effort of endeavoring to charge the memory with a page number, 20 are obviated. As the reader ceases reading, he has merely to touch the edges of the disks to indicate the page and when he wishes to resume reading a glance at the recorder instantly gives him his page number.

25 It will be understood that changes from the exact structure shown herein may be made within the scope of the accompanying claims, without departing from the principles of the invention.

30 What I do claim as my invention and desire to secure by Letters Patent, is:

1. The combination with a book cover comprising a plurality of cover members attached together face to face, of a page indicator comprising a plurality of independently movable members movably mounted between two of said cover members, each of said movable members having a plurality of numerals thereon, and being accessible 35 from the exterior of the cover so as to be moved as required, said cover being apertured to expose one numeral on each of said movable members to permit simultaneous observation thereof, whereby they may be 40 read as one number.

45 2. The combination with a book cover comprising a plurality of cover members attached together face to face, of a page indicator comprising a plurality of rotatable disks located between two of said cover members, each of said disks having a plurality of numerals thereon, and each disk overlapping another of said disks, and being also accessible from the exterior of the cover so 50 as to be moved as required, said cover being apertured to expose one numeral on each of said movable disks to permit simultaneous observation of such numerals, whereby the numbers upon the disks, and the apertures 55 through which they show may be relatively close together, and said numbers may be read as one number.

60 3. The combination with a book cover comprising a plurality of cover members, one of said members being a lining sheet at-

tached to the other of said cover members, of a page indicator comprising a plurality of independently movable members located between said lining sheet and the other cover member, each of said movable members carrying a plurality of numerals thereon, one of said cover members being apertured to expose, and thus permit simultaneous observation of, one numeral on each of said movable members, whereby said opposed numerals 70 may be read as one number.

4. The combination with a book cover comprising a plurality of cover members, one of said members being a lining sheet attached to the other of said cover members, of a page indicator comprising a plurality of independently movable members located between and movably mounted upon one of said cover members, each of said movable members having a plurality of numerals 80 thereon, one of said cover members being apertured to expose and thus permit simultaneous observation of one numeral on each of said movable members, whereby said exposed numerals 85 may be read as one number.

5. The combination with a book cover comprising a plurality of cover members, one of said members being a lining sheet attached to the other of said cover members, of a page indicator comprising a plurality 90 of rotatable members located between said cover members, and mounted upon one of said cover members, each of said rotatable members having a plurality of numerals thereon, one of said cover members being 95 apertured to expose, and thus permit simultaneous observation of, one numeral on each of said rotatable members, whereby said exposed numerals 100 may be read as one number.

6. The combination with a book cover comprising a plurality of cover members, one of said cover members being a lining sheet attached to the other of said cover members, of a page indicator comprising a plurality of rotatable numeral bearing disks 105 located between said cover members and rotatably mounted upon one of said cover members, the edge of each disk projecting beyond the edge of the cover, one of said cover members being apertured to expose 110 and thus permit simultaneous reading of one numeral on each of said disks, whereby said exposed numerals 115 may be read as one number.

7. The combination with a book cover 120 comprising a plurality of cover members, one of said members being a lining sheet attached to the other of said cover members, of a page indicator comprising a plurality of numeral bearing disks rotatably mounted 125 in a row between two cover members, the edges of said disks projecting past the edge of the cover, a plurality of orifices formed in one of said cover members, each orifice being of a size to expose a single numeral 130

and being arranged in a row in line with said disks, whereby one numeral on each disk is exposed and may be simultaneously observed to be read as one number.

5 8. The combination with a book cover comprising a plurality of cover members attached together face to face, of a page indicator comprising a plurality of independently movable members movably mounted 10 between two of said cover members and overlapping one another, each of said movable members having a plurality of numerals thereon, and being accessible from the exterior of the cover so as to be moved as

required, said cover having a plurality of 15 apertures, each being of a size to expose one numeral on each of said movable members to permit simultaneous observation thereof, whereby the apertures are brought relatively close together and the numerals on the respective members may be read as one number. 20

In testimony whereof, I have signed my name to this specification in the presence of two subscribing witnesses.
